UNITED STATES PATENT OFFICE.

EDWARD A. ILLIG, OF ERIE, PENNSYLVANIA, ASSIGNOR OF ONE-HALF TO EDWARD F. SHUGART, OF ERIE, PENNSYLVANIA.

SEWING-MACHINE ATTACHMENT.

1,173,973.

Specification of Letters Patent. Patented Feb. 29, 1916.

Application filed July 8, 1915. Serial No. 38,735.

To all whom it may concern:

Be it known that I, EDWARD A. ILLIG, a citizen of the United States, residing at Erie, in the county of Erie and State of Pennsylvania, have invented a new and useful Sewing-Machine Attachment, of which the following is a specification.

The device forming the subject matter of this application is adapted to be employed for applying the under thread in a sewing machine, directly from a spool, thereby dispensing with the use of a bobbin.

The invention aims to provide novel means for holding the spool in place so that it may rotate on its axis, and to provide novel means for applying the thread directly from the spool without the interpolation of a bobbin or shuttle, such a construction, obviously, doing away with bobbin winding.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows the invention in front elevation; Fig. 2 is a side elevation; Figs. 3 and 4 are cross sections, Fig. 3 being taken on the line 3—3 of Fig. 1 and Fig. 4 being taken on the line 4—4 of Fig. 1; Fig. 5 is a perspective view showing the actuating shaft and the driving head which is carried thereby; Fig. 6 is a perspective view showing the interior of the back portion of the spool carrier; Fig. 7 is a sectional detail enlarged from Fig. 4.

In carrying out the present invention there is provided a bearing 1 which may be assembled in any desired manner with a portion of the frame work of a sewing machine (not shown). At spaced points throughout its periphery, the bearing 1 is equipped with outstanding lugs 2. In the

bearing 1 there is formed a chamber 3 and in the rear wall 4 of the bearing 1 there is an opening 5 in which is journaled for oscillating movement, the usual shaft 6 which constitutes a part of a sewing machine of known and approved type. To one end 7 of the shaft 6 is secured a driving head 8 in the forward face of which is formed a concavity 9. Located adjacent the rim of the driving head 8 and adjacent the periphery of the concavity 9 are forwardly presented driving lugs 10. The bearing 1 is flattened slightly on top, or is cut away, thereby forming an opening 12 which communicates with the chamber 3. The driving head 8 is located in the chamber 3 and rotates with the shaft 6 in close relation to the rear wall 4 of the bearing 1.

In carrying out the invention there is provided a spool holder which is a composite structure, the same including a back 14, the rear face of which is convexed as shown at 15, so that the back may enter the concavity 9 of the driving head 8, the back, for the most part, lying in the chamber 3 of the bearing 1. The back 14 comprises a marginal flange 16, which, as shown in Fig. 4, coöperates with the forward edge of the bearing 1. Throughout a portion of its periphery, the back 14 of the spool holder is cut away as shown at 17, thereby removing a portion of the flange 16, one end of the flange 16 terminating in a loop-taking hook 18 adapted to coöperate with the needle thread of the sewing machine. In the rear wall of the back portion 14 of the spool holder there are formed openings 19 which are adapted to receive the lugs 10 on the driving head 8, to the end that when the driving head is rotated, the back portion 14 of the spool holder may be rotated also. In the forward face of the back 14 there is a semicylindrical recess 20, the space between the recess 20 and the flange 16 constituting a shoulder 22.

The spool holder comprises, further, a front 23 which is convexed as shown at 33. Throughout a portion of its periphery, the front 23 of the spool holder is flattened as shown at 25, there being located, partly in the flattened portion 25 of the front and partly in the circumferential wall thereof, a needle receiving opening 24. The front 23 of the spool holder fits within the contour of the flange 16 of the back and abuts 110

against the shoulder 22. In the rear face of the front 23 of the spool holder is formed a semi-cylindrical recess 26 which, coöperating with the recess 20 in the back 14, is 5 adapted to receive a spool, the end flanges or walls of which are shown at 28 in Fig. 1, the front 23 of the spool holder being equipped with parallel slots 27, in which the flanges 28 of the spool are loosely received, the construction being such that the 10 spool is held in place for rotation about its axis, in the recess 26 and 20, the spool at the same time, being adapted to rotate with the spool holder, comprising the parts 14 and 23, when the spool holder rotates with the driving head 8 and the shaft 6. In the 15 back 14 there is a recess 21 receiving the inner end of a latch 101 mounted to swing on a pin 102 passed through the back transversely, the latch 101 being provided at its 20 forward end with a head 103. In the front 23 there is a slot 29 in which the head carrying end of the latch 101 is mounted to move, the front being provided with a shoulder 107 with which the head 103 of the latch is adapted to engage. A spring 104 bears against the head 103 of the latch 101 to maintain the head of the latch engaged with the shoulder 107, the spring 25 104 being hooked as shown at 105, if desired, around the pin 102. The back 14 may be provided with a dowel pin 108 received in a recess in the front 23. The front 23 of the spool holder is equipped with a central 30 opening 32 through which passes the thread carried by the spool.

Applied to the forward face of the bearing 1 is a collar 30, the same being held in place by means of screws 35 which enter the 40 lugs 2 of the bearing 1. The top of the collar 30 is flattened as shown at 36 and is cut away as shown at 37 to define an opening coöperating with the opening 12 of the bearing 1. The collar 30 holds the spool carrier 14—23 in place on the bearing 1 for 45 rotation and so positions the spool carrier that the openings 19 in the back 14 of the spool carrier are held in engagement with the lugs 10 on the driving head 8. In the 50 inner edge of the collar 30 there is formed

a race 31 and in this race the flange 16 of the back 14 of the spool holder is received for oscillating or rotary movement.

The operation of the device will be understood clearly in view of the well known 55 function of an oscillating shuttle but it is to be observed that in this device no shuttle or bobbin is necessary, the spool being mounted directly in the spool holder or carrier and the carrier being so constructed 60 that the spool may readily be inserted in place. When it is necessary to replace the spool, the head 103 of the latch 101 is pressed down against the action of the spring 104, the head being disengaged from 65 the shoulder 107, whereupon the front may be removed.

Having thus described the invention, what is claimed is:—

1. In a sewing machine, a spool carrier 70 embodying a front and a back having complementary recesses defining a spool receiving chamber, the front having parallel slots therethrough adapted to receive the flanges of a spool to hold the latter against endwise movement and for rotation and to render the spool accessible for manipulation; means for detachably uniting the front and the back; and means for rotating the carrier. 75

2. In a sewing machine, an annular support; a spool carrier embodying a back having an outstanding flange coacting with the outer edge of the support; a ring applied to the support and provided with a race receiving the flange; a front; and means for 80 securing the front to the back detachably; the front and the back being provided with complementary, spool receiving recesses, the support and the ring being provided with 85 coöperating openings in their tops, and the front having a circumferential slot adapted to coöperate with the opening in the ring. 90

In testimony that I claim the foregoing as my own, I have hereto affixed my signature in the presence of two witnesses.

EDWARD A. ILLIG.
